UNITED STATES PATENT OFFICE

EDWIN BECKER, OF BERLIN-HERMSDORF, GERMANY

PROCESS OF MANUFACTURING GRINDING AND POLISHING DISKS

No Drawing. Application filed April 6, 1927, Serial No. 181,598, and in Germany March 16, 1926.

It is known to give to grinding and polishing disks to be produced in pressing-moulds a dense structure preferably towards the centre by giving to the disk a first shape in which the dimensions of the disk are greater towards the middle than they are intended to be in the final shape. This was effected in such a manner that the preliminary shape was produced in one mould and the final shape in a second mould.

This manufacturing method presents the inconvenience that the mould has to be changed, and it presents the danger that during the changing of the mould the kneadability decreases so that the preliminarily moulded disk easily crumbles to pieces in the second mould.

To obviate these inconveniences the material is pressed, according to the invention, in one and the same pressing mould first to the coarse preliminary shape by corresponding gradual accumulation of the material at those points on which the greater density has to be obtained, whereupon with the aid of pressing rams shaped in accordance with the final shape this final shape is given to the material.

According to the improved method the mass filled into the pressing mould is not distributed uniformly but in an inclined plane rising from the edges to the centre and compressed accordingly, so that the preliminary shape is given to the material. In the same pressing mould the final shape is given to the material by pressure, after the upper pressing ram has been inserted into the mould. For equalizing the densities, the pressing mould with the material is then turned upside down and a second compressing is carried out.

I claim:—

A process of pressing grinding and polishing disks by irregular density by heaping the material on the point of the intended compression, consisting in distributing the material in the mould from the edge towards

the center in an ascending plane, in submitting the material to a first pressing so that the curvature of the surface almost disappears, in turning the mould with the pressed body upside down, and in pressing the pressed body again to obtain the final shape.

In testimony whereof I affix my signature
EDWIN BECKER.
